UNITED STATES PATENT OFFICE.

ADIEL Y. DODGE, OF SOUTH BEND, INDIANA, ASSIGNOR TO BENDIX BRAKE COMPANY, OF CHICAGO, ILLINOIS, A CORPORATION OF ILLINOIS.

METHOD OF MAKING BRAKE SHOES.

Application filed July 27, 1925. Serial No. 46,242.

This invention relates to the manufacture of brake shoes, and will be described as carried out in making shoes of pressed metal blanks.

5 Heretofore, in the manufacture of brake shoes of sheet metal, most earlier shoes having been channel-shaped in cross-section, it has been the practice to have the face of the forming member engage the cylindrical 10 lining-supporting part, or friction face, of the shoe, which cylindrical face therefore bottoms in the die. When the pressure is relieved, and the formed blank is removed, there is invariably more or less return 15 "spring" of the curved pressed friction face, and this spring is variable and injects an uncontrollable factor which makes exact results difficult, many rejections being necessary to secure accurate interchangeability 20 of the shoes.

According to the present invention, the blanks and shoes are formed by a novel process including, as a very important step, the pressing of the blanks with the material of 25 the flat shoe web in engagement with the face of the forming member and with the cylindrical flange formed by a drawing action between the side of the forming member and the side of the die. As is well 30 known, great accuracy can be secured, in such a drawing action, while the web which bottoms in the die, being flat, has no uncontrollable "spring" to be considered, and moreover the accuracy of the stiffening web 35 is not very important.

The above and other objects and novel steps contemplated by the invention, together with novel features of the formed blanks, will be understood from the following description of one application of the invention as illustrated by the accompanying drawings, in which:

Fig. 1 is a vertical section through the brake, just inside the wheel, showing the 45 shoes in side elevation;

Fig. 2 is an outside elevation of one of the end shoes, before the brake lining is attached;

Fig. 3 is a side elevation of the same shoe;

50 Fig. 4 is a section through the shoe on the line 4-4 of Fig. 3;

Fig. 5 is an inside elevation of the shoe;

Fig. 6 is a section through one of the blanks and the forming member and die;

Fig. 7 is a similar view showing the use 55 of a different die; and

Fig. 8 is a plan view of one of the blanks. In the arrangement of Fig. 1, the brake includes a drum 10 and backing plate 12, between which are arranged three brake shoes 14, 16, and 18, shoes 14 and 18 being interchangeable and identical. Shoe 14 is anchored at 20 and shoe 16 at 22, and shoe 18 is pivotally connected to shoe 16 by a pin 24. The shoes are expanded against the 60 drum 10 by means such as a double cam 26, against the resistance of springs 28 and 30.

The shoe 14 is illustrated in Figs. 2-5, and the method of making it in Figs. 6-8; 70 the construction and method of manufacture of the other shoes being substantially the same. As best appears in Fig. 4, the shoe is built up of two pressed parts or stampings, made from blanks such as "B" in Fig. 8, 75 and each generally L-shaped in cross-section. Thus the two stampings have substantially flat radial web portions 32, spread apart at the anchored end of the shoe to form parallel arms 34 straddling the end of shoe 16 80 (Fig. 1) and provided with openings 36 to give ample clearance for anchor 22.

Around the edge of each stamping runs a continuous flange 38, wide enough on the outside of the shoe so that the aligned 85 flanges of the two stampings form the friction face of the shoe and directly support the brake lining 40 (Fig. 1). The two stampings are arranged back to back and fastened together, e. g. by means of rivets 90 42 passing through the two web portions 32. A plate 44 may bridge the arms 34 to lengthen the friction surface and strengthen 95 the shoe. A wear plate 46 for cam 26 is secured to the radial end parts of flanges 38. An opening 48 is provided for one of two parts 50 carrying a plate 52 positioning the shoes laterally.

According to an important step in the manufacture of the shoes, after each blank 100 "B" is cut out (or at the same time, if desired), it is pressed to shape between a forming member 60 and a die 62 (Fig. 6) or 64 (Fig. 7), with the web material 32 in engagement with the face of the forming member. Thus the material bottoming in the die 62, or pushed into the open die 64, 105 is the flat web of the blank, which has no

tendency to "spring" back, whereas the flange 38, the accuracy of which is highly important, is drawn between the side of the forming member 60 and the side of the die

5 62 or 64. Web 32 is depressed different distances into the die, to form the offset arm 34.

While one particular shoe, and one particular way of making it, have been described in detail, it is not my intention to 10 limit the scope of the invention by that description, or otherwise than by the terms of the appended claims.

I claim:

1. That method of forming pressed metal 15 brake shoes which includes the steps of (a) cutting integral blanks, each including web material and flange material, and (b) pressing each blank by a forming member into a die, with the face of the forming member 20 engaging the flat web of the shoe and with the opposite sides of the forming member co-operating with the opposite sides of the die to draw out two flanges along the inner and outer edges of said web, the flange along the 25 outer edge being cylindrical.

2. That method of forming pressed metal 30 brake shoes which includes the steps of (a) cutting integral blanks, each including web material and flange material, and (b) pressing each blank by a forming member into a die, with the face of the forming member 35 engaging the flat web of the shoe and with the sides of the forming member co-operating with the sides of the die to draw out a continuous flange extending entirely around

the edge of the web, the parts of said flange along the inner and outer edges of the web being curved, and the outer part having a true cylindrical surface.

3. That method of forming pressed metal 40 brake shoes which includes the steps of (a) cutting integral blanks, each including web material and flange material, and (b) pressing each blank by a forming member into a die, with the face of the forming member 45 engaging the flat web of the shoe and with the sides of the forming member co-operating with the sides of the die to draw out a cylindrical flange extending along the outer edge 50 of the web and a substantially radial flange at the end of the shoe, and (c) assembling two of the formed blanks back to back and arranging a wear plate across the joint at the end of the shoe and fastening it to said 55 radial flanges.

4. That method of making brake shoe sections which comprises the operations of drawing two reversely contoured sheet metal parts each having a curved web and a laterally-extending arcuate flange thereon, assembling the said parts with the webs back to back at one portion of their length and separated at another and with the arcuate flanges in axial alinement to present a widened support for a brake lining, and connecting the 60 abutting portions of the web to form a unitary structure.

In testimony whereof I have hereunto signed my name.

ADIEL Y. DODGE.
